Primary Examiner — Darlington Ly*Assistant Examiner* — Jeremy Koenig(74) *Attorney, Agent, or Firm* — Lina A. Asmar; L.A. LAW, PLLC(57) **CLAIM**

The ornamental design for a wheel, as shown and described.

DESCRIPTION

FIG. 1 is a perspective view of a wheel according to the present invention; and,

FIG. 2 is a front elevation view thereof.

The broken lines depict portions of the wheel that forms no part of the claimed design.
